UNITED STATES PATENT OFFICE.

DAVID LIPPY, OF MANSFIELD, OHIO.

CAR-COUPLING.

SPECIFICATION forming part of Letters Patent No. 349,726, dated September 28, 1886.

Application filed December 11, 1885. Serial No. 185,395. (No model.)

To all whom it may concern:

Be it known that I, DAVID LIPPY, of Mansfield, in the county of Richland and State of Ohio, have invented certain new and useful 5 Improvements in Car-Couplings; and I do hereby declare the following to be a full, clear, and exact description of the invention, such as will enable others skilled in the art to which it appertains to make and use the same.

10 My invention relates to an improvement in car-couplings, the object being to provide an automatic coupler with devices for enabling the coupler to be readily detached on any grade, and thus enable the train to be cut in 15 two when moving on upgrade or making a flying switch without necessitating a slackening of speed.

A further object is to provide detaching and 20 automatic coupling devices that shall be simple and durable in construction, of small initial cost, and adapted to be applied or combined with draw-heads, so that they may be used in connection with cars furnished with the ordinary links.

25 With these ends in view my invention consists in certain features of construction and combinations of parts, as will be hereinafter described, and pointed out in the claims.

In the accompanying drawings, Figure 1 is 30 a view of the draw-heads of two adjacent cars provided with my improved coupling. Fig. 2 is an end view of one of the couplings, partly in section. Fig. 3 is a longitudinal section of the two couplings when connected. Fig. 4 is 35 a perspective view of one of the couplings, and Fig. 5 is a modified form of lock-bar.

40 A A represent the draw-heads of two adjacent cars, each provided with my improvement. As the draw-heads are similar in construction, I will describe one of them only.

Draw-head A is constructed with the flanges 45 B and C, formed on each side of the recess D, by means of which lateral displacement of the opposite draw-head is prevented, the forward portion of the draw-head forming a guide, E. Within the draw-head is formed a socket, F, in the rear of which is pivotally secured the locking-jaw G by means of a vertical bolt, H, secured in the head. The jaw 50 is provided with the laterally-projecting shoulder I, the forward portion of which is beveled, as shown, whereby the jaws upon opposite

draw-heads are conveniently forced into the interior of the recess D, and the inner edges of the shoulders I are clamped in position. 55 Extending through the outside of the draw-head and opening into the socket F is formed the slot or opening J, through which passes the arm K, secured to the rear of the locking-jaw G, or formed integral therewith, as preferred. The outer end of said arm is provided transversely with the perforation L, adapted to receive a link, M, or other connecting device attached to the gravity-bar N, the said bar being pivotally secured between the 60 arms O, formed integral with the draw-head at or near the top thereof. The inner end of the gravity-bar N is beveled downwardly and inwardly, as shown, and the link or connecting device M is attached thereto in such manner that when the bar is adjusted horizontally relative to the draw-head the shoulder I is drawn within the socket F. Near the center of the gravity-bar is pivotally attached the 65 rod P, which extends to the top of the car, and 70 is provided at its upper end with the handle Q. To the top of a car, or near thereto, is secured a rest, R, provided at its outer end with a hole, S, through which passes the rod P. The bar is loosely mounted at its lower end 75 in a suitable socket, which will permit the bar to be rotated. The rest R is provided with a hook, S', to which one of the arms, T, of the bar is secured when it is desired to elevate the 80 gravity-bar and prevent the operation of the 85 coupling devices.

When in use upon platform-cars, the car may be provided with a suitable hook, and the lower arm can be used to secure the rod in elevated position. When it is desirable to 90 dispense with the rod P, the locking-jaw G can be locked out of possible action by inserting a pin through the perforation U, formed in the arm K.

When the cars are coupled, by raising the 95 rod P, the gravity-bar N is elevated and the locking-jaw G will be drawn into the socket F, thereby detaching the couplings. When the rod P or gravity-bar N is lowered, the lower beveled end thereof will bear against 100 the end of the arm K, thereby forcing the locking-jaw out of the slot, and the same is ready for adjustment.

In the modification shown in Fig. 6 the

draw-head is provided with the recess D and the flanges B and C, by means of which lateral displacement is prevented. The guide-frame *a* is provided transversely with the vertically-5 elongated slot *b*, in the rear of and adjoining which is secured the laterally-extending bracket *c*, the head *d* of which is provided with the vertically-elongated slot *e*. A locking-jaw, *f*, is located in the said slots *b* and *e*, and is secured to a gravity-bar, *g*, by means of the arm or pin *h*, which is rigidly secured thereto, the said pin passing through the elongated slot *i*, formed in the side of the bracket *c*. The gravity-bar *g* is pivotally secured to the side of the 15 bracket, and is loosely attached to the pin *h* by means of the vertically-elongated slot *j*, formed in the pivoted end of the bar.

The action of the modified form is similar to that described in the preferred construction, 20 and the same can also be provided with rod *P*, adapted to be operated as described.

By my improved car-coupler the cars may be automatically coupled without requiring the brakeman to enter between the cars, as the 25 locking-jaws are in constant adjustment unless otherwise placed. The cars can be conveniently uncoupled from either side or from the top.

As it is evident that many slight changes in 30 the construction and relative arrangement of parts might be resorted to without departing from the spirit of my invention, I would have it understood that I do not restrict or limit myself to the exact construction and arrangement 35 of parts shown and described.

I am aware that it is old to provide a draw-head with a bell-crank lever pivoted at its elbow within the coupler, and provided at one end with an arrow-head for engaging a similar 40 device on the adjacent draw-head and, at its opposite end with a weight; and also that it is old to construct a draw-head with projecting parts for engaging correspondingly-shaped recesses in the adjacent draw-head, and with a 45 pivoted jaw for engaging the jaw of said adjacent draw-head, and hence I make no claim, broadly, to such constructions.

Having fully described my invention, what I claim as new, and desire to secure by Letters 50 Patent, is—

1. In a car coupling, the combination, with a draw-head and locking-jaw secured thereto, of a gravity-bar pivotally secured to said draw-head and pivotally connected with the jaw, whereby the same is automatically locked, 55 substantially as set forth.

2. In a car-coupling, the combination, with a draw-head having a slot formed in one side thereof, of a locking-jaw pivoted in said slot and a gravity-bar pivotally secured to said draw-head and pivotally connected to said jaw, whereby the jaw is automatically locked, 60 substantially as set forth.

3. In a car-coupling, the combination, with a draw-head and a slot or recess formed in the 55 guide-bar thereof, of a jaw pivoted in said recess, an arm formed laterally on the jaw extending through said guide-bar and pivotally connected to a gravity-bar, whereby the jaw is automatically locked, substantially as set 70 forth.

4. In a car-coupling, the combination, with a draw-head having a recess or slot formed therein, of a locking-jaw pivoted in said recess and pivotally connected with a gravity-bar 75 and means for locking the jaw out of possible engagement, substantially as set forth.

5. In a car-coupling, the combination, with a draw-head and a locking-jaw secured thereto, the said jaw having a laterally-extending 80 arm through said bar, of a gravity-bar pivotally secured to said arm, and an upright rod pivotally secured to the bar, and means for locking the rod in vertical adjustment, substantially as set forth.

6. The combination, with a draw-head provided with a side extension, of a lock-bar pivotally secured in said extension and a gravity-bar for automatically throwing the lock-bar into locked adjustment, substantially as set 90 forth.

In testimony whereof I have signed this specification in the presence of two ~~subscribing~~ witnesses.

DAVID LIPPY.
